UNITED STATES PATENT OFFICE.

WILLIAM A. LORENZ, OF HARTFORD, CONNECTICUT, ASSIGNOR TO THE OTAKA FABRIC COMPANY, OF HARTFORD, CONNECTICUT, A CORPORATION OF CONNECTICUT.

PAPER-CRINKLING MACHINE.

Application filed November 5, 1920. Serial No. 422,005.

To all whom it may concern:

Be it known that I, WILLIAM A. LORENZ, a citizen of the United States, residing in Hartford, in the county of Hartford and 5 State of Connecticut, have invented certain new and useful Improvements in Paper-Crinkling Machines, of which the following is a specification.

This invention relates to means for working paper, as by corrugating the same longitudinally and crinkling it transversely.

The object of the invention is to provide a simple, inexpensive and efficient apparatus for corrugating the paper longitudinally, 15 and also to improve and simplify the means for crinkling the paper after it is corrugated.

Heretofore, the operation of corrugating or forming longitudinal flutings in the web has involved gathering the web widthwise, 20 for making the corrugated web less in width than the original web, since considerable of the width of the paper is taken up in making the corrugations.

I have found that by liberally wetting the 25 paper as it unwinds from the supply roll, so that the moisture permeates the web throughout, a tendency is set up for the web to expand laterally by reason of the presence of the moisture, and also that the application 30 of the moisture to the web renders it plastic and somewhat stretchable. Advantage is taken of both of these conditions, to present the moistened web directly to the corrugating rolls, without previously plaiting or 35 gathering the web into longitudinal grooves. Owing partly to the natural expansion of the wet web and partly to its plastic or stretchable condition, I have found that deep corrugations can be formed in the web directly 40 by the corrugating rolls. The corrugated web, when sufficiently dried, may be of substantially the same width as the original web, although it will be found somewhat reduced in thickness or weight, by reason of 45 the stretching.

The web, while still moist, may be carried around one of the corrugating rolls to be presented to a doctor-blade, whereby it is transversely crinkled and also stripped from the roll; this being preferably done before 50 the paper is fully dried. The roll which co-

operates with the doctor-blade is preferably of large diameter, and preferably heated, so that the fluted web is exposed to the heat in passing around the same, thus rendering the 55 web better adapted for crinkling, and tending to secure a better product.

For augmenting the efficiency of the crinkling cylinder, and co-operating with it to corrugate the web, and enabling it to crush 60 the web against the doctor-blade with sufficient force to produce the required crinkling, there is preferably employed an endless belt to run upon said cylinder or drum, from the introductory side thereof to a point close to 65 said doctor-blade. At this point the belt leaves the cylinder, and then runs over guide pulleys back to the introductory side of the cylinder again.

By carrying the belt close to the doctor- 70 blade, so that only a narrow space is left between the blade and the belt where the paper leaves the cylinder, an efficient crinkling device is produced, because the forcing of the paper to advance through such confined space has the effect of producing or 75 favoring the desired crinkling action.

Another feature of the invention resides in the means for deepening, improving and 80 fixing the corrugations in the web, and for this purpose the belt is provided with surface ridges throughout its width, to match and run within the peripheral grooves within the crinkling cylinder, whereby the paper is pressed or compacted into said peripheral 85 grooves during all the time that it is under the control of said belt.

Other features and advantages will hereinafter appear.

In the accompanying drawings,

Figure 1 is a plan of one form of paper-working machine embodying the present improvements.

Figure 2 is a sectional elevation thereof taken at about the line 2-2 of Figure 1. 95

Figure 3 is a sectional elevation on a larger scale, showing the crinkling means, and taken at about the line 3-3 of Figure 1.

Figure 4 is a plan to illustrate the relation of the grooved doctor-blade to the 100 crinkling cylinder.

Figure 5 is a cross-section of the endless

belt which is employed to hold the paper onto the drum.

The apparatus comprises a support 10 for a web of paper in the form of a roll 11, the rotation of which is retarded by a weighted friction strap 12.

From the roll the paper is led at 13 directly to a pair of peripherally-grooved corrugating rolls 14, 15; but before entering the bight of said rolls the paper, which may be porous or absorbent, is liberally wet on both sides by sprinkler pipes 16, 17.

The paper, before the rolling action takes place, may be rendered so wet that it tends to expand laterally, and also so that it is plastic and slightly stretchable, so that it will yield to the incidental stretching action of the rolls without becoming torn or broken.

20 The roll, cylinder or drum 15 is made of relatively large diameter, and may be provided with a steam pipe 18 to heat the paper.

25 Running upon the cylinder 15 is an endless belt 19. This passes over rolls and pulleys 20, 21, 22, 23. The roll 20 is arranged near the roll 14, where the paper runs onto the cylinder 15; and the roll 23 is arranged at the delivery side or portion of cylinder 15, and close to a doctor-blade 24. The belt 19 may, therefore, run around the cylinder 15 for more than half of its circumference; and said belt may be depended upon to improve or augment the corrugating action upon the paper, as well as to take an important part in the crinkling operation, as hereinafter explained. For aiding in the forming or compacting of the grooves in the paper, and for holding the 40 same firmly in the grooves in the cylinder 15, the belt may be provided with longitudinal ridges or ribs 25, to enter the corrugating peripheral grooves 26 in the cylinder; said grooves corresponding to the 45 grooves 27 in the companion roll 14. The ribs 25 on the belt are rounded, and the ribs 28 on the cylinder are also rounded, and the belt fits tightly throughout to the cylinder, so that it may pack the sheet into the 50 grooves in the cylinder, and thus aid in the operation of corrugating the paper; the latter being more readily worked at this time because the heat of the cylinder acts to diffuse the moisture throughout the paper.

55 As the web travels around the cylinder, it tends to become heated and less moist, so that it reaches an excellent condition for crinkling.

60 The paper may be so absorbent that it will readily take up all the water that is required, so that it may be rolled into corrugations without preliminary plaiting or gathering; and in the case of heavier paper, or paper having more sizing, other means

may be provided for securing thorough wetting thereof.

The belt 19 aids the cylinder 15 in carrying the paper against the doctor-blade 24 and forcing it through the narrow space left between said doctor-blade and the roll 23, over which the belt turns; the crinkling of the paper being indicated at 29, and the crinkled paper being carried by a delivery belt 30.

The machine may be driven by a belt 31 and pulley 32, the latter having a pinion 33 to mesh with a gear 34, which is connected to the main corrugating and crinkling cylinder 15. Said gear 34 may mesh with a pinion 35, which is connected to the corrugating roll 14. Also meshing with said gear is a pinion 36, connected with the crinkling roll 23.

The pressure of the roll 23 may be produced by a spring 37, which is regulatable by a screw 38 provided with a lock-nut 39.

Variations may be resorted to within the scope of the invention, and portions of the improvements may be used without others.

Having thus described my invention, I claim:

1. The combination of a means for holding a supply roll of paper, corrugating rolls to which the paper is directly led from the supply roll, means between the corrugating rolls and the supply roll for wetting the paper, and an endless power-driven belt running upon one of said corrugating rolls to hold the paper thereto, and formed to press the same into the corrugations. 100

2. The combination of a means for holding a supply roll of paper, corrugating rolls to which the paper is directly led from the supply roll, means between the corrugating rolls and the supply roll for wetting the paper, an endless power-driven belt running upon one of said corrugating rolls to hold the paper thereto, and formed to press the same into the corrugations, and a doctor-blade to co-operate with the roll upon which said belt runs. 105

3. The combination of a means for holding a supply roll of paper, corrugating rolls to which the paper is directly led from the supply roll, means between the corrugating rolls and the supply roll for wetting the paper, an endless power-driven belt running upon one of said corrugating rolls to hold the paper thereto, and formed to press the same into the corrugations, a doctor-blade to co-operate with the roll upon which said belt runs, and means for heating said roll. 115

4. The combination of a means for holding a supply roll of paper, corrugating rolls to which the paper is directly led from the supply roll, means between the corrugating rolls and the supply roll for wetting the paper, and an endless power-driven belt 125

running upo none of said corrugating rolls to hold the paper thereto, said belt having longitudinal ribs to press the paper into the grooves on said roll.

5. The combination of a means for holding a supply roll of paper, corrugating rolls to which the paper is directly led from the supply roll, means between the corrugating rolls and the supply roll for wetting the paper, an endless power-driven belt running upon one of said corrugating rolls to hold the paper thereto, and a doctor-blade to co-operate with the roll upon which said belt runs, said belt running on the intake side 10 of said roll to a point in proximity to said doctor-blade, to produce a reduced passage through which the paper is crushed and whereby it is transversely crinkled.

6. In an apparatus for working paper, the combination of means for wetting the paper; a pair of peripherally-corrugated rolls for longitudinally corrugating the web of paper; a corrugated carrying belt engaging one of said rolls; and a roll for deflecting the belt away from the carrier 20 roll.

7. In an apparatus for working paper, the combination of means for wetting the paper; a pair of peripherally-corrugated members, one of which is a cylinder and the other of which is a roll for longitudinally corrugating the web of paper; a corrugated carrying belt engaging said cylinder; a roll for deflecting the belt away from the carrier 30 roll; and a corrugated doctor-blade engaging the surface of the cylinder.

8. In an apparatus for crinkling paper, means for wetting or dampening the web of paper; means, including two annularly-corrugated members, one of which is a cylinder and the other of which is a roll, for corrugating the wet web of paper longitudinally; a carrier belt engaging the web of paper as it passes over the cylinder; a roll for carrying this belt away from the cylinder; and a corrugated doctor-blade engaging the surface of the cylinder.

9. In an apparatus for crinkling paper, means for wetting or dampening the web of paper; corrugated members, one of which is a cylinder and the other of which is a roll for corrugating the wet web of paper longitudinally; a corrugated carrier belt engaging the web of paper as it passes over said cylinder; a roll for carrying this belt away from the cylinder; and a corrugated doctor-blade engaging the surface of the cylinder.

10. In an apparatus for crinkling paper, means for wetting or dampening the paper; a pair of annularly-corrugated members, one of which is a cylinder and the other of which is a roll for longitudinally corrugating the web of paper; a corrugated carrying belt engaging said cylinder; a corrugated doctor-blade engaging the surface of the cylinder; and a deflecting roll arranged in proximity to the doctor-blade for deflecting the belt away from the carrier cylinder.

gated doctor-blade engaging the surface of the cylinder; and a deflecting roll arranged in proximity to the doctor-blade for deflecting the belt away from the carrier cylinder.

11. In an apparatus for crinkling paper, means for wetting or dampening the web of paper; means for corrugating the wet web of paper longitudinally between two annularly-corrugated members, one of which is a cylinder and the other of which is a roll; a carrier belt engaging the web of paper as it passes over the cylinder; a roll for carrying this belt away from the cylinder, and in proximity with the doctor-blade, and a corrugated doctor-blade engaging the surface of the cylinder.

12. The combination of a corrugating roll, and an endless belt to run upon said corrugating roll to hold the paper thereto and press the same into the corrugations.

13. The combination of a corrugating roll, an endless belt to run upon said corrugating roll to hold the paper thereto and press the same into the corrugations, and a doctor-blade to co-operate with said roll.

14. The combination of a corrugating roll, and an endless belt to run upon said corrugating roll to hold the paper thereto and press the same into the corrugations, said belt having longitudinal ribs to press the paper into the grooves on said roll.

15. In an apparatus for crinkling paper, means for wetting or dampening the web of paper; means for corrugating the wet web of paper longitudinally, including a corrugated roll and a corrugated carrier belt engaging the web of paper as it passes over said roll; and a corrugated doctor-blade engaging the surface of the roll.

16. The process of liberally wetting a flat web, so that the moisture permeates the web throughout and sets up a tendency for the web to expand laterally, and also renders the web plastic and stretchable; corrugating the moist flat web longitudinally and deeply by feeding it directly to corrugating rolls; the corrugated web having substantially the same width as the original flat web; and stripping the web from one of said rolls by means of a crinkling device.

17. The process of liberally wetting a flat web, so that the moisture permeates the web throughout and sets up a tendency for the web to expand laterally, and also renders the web plastic and stretchable; corrugating the moist flat web longitudinally and deeply by feeding it directly to corrugating rolls; the corrugated web having substantially the same width as the original flat web; stripping the web from one of said rolls by means of a crinkling device; and holding the web in the corrugations on the roll by means of a flexible traveling device.

18. The process of liberally wetting a flat web so that the moisture permeates throughout and sets up a tendency for the web to expand laterally, and also renders the web plastic and stretchable, and corrugating the moist flat web longitudinally by feeding it directly to corrugating rolls, said web being supported over a substantial area on one

of said rolls before the web is corrugated, and on another of said rolls after it is corrugated whereby to prevent the web from narrowing and maintaining the web of substantially the same width as the original flat web. 10

WILLIAM A. LORENZ.
